GAS TURBINE

William M. Nichols, Schenectady, N. Y., assignor
to American Locomotive Company, New York,
N. Y., a corporation of New York

Application May 21, 1947, Serial No. 749,433

1 Claim. (Cl. 60—41)

1

This invention relates to gas turbines.

The object of the present invention is to obtain greater efficiency in a gas turbine, as well as to eliminate the need of a bulky heat exchanger in order to obtain this efficiency. Most gas turbines operate on either the constant volume (explosion) cycle or on the constant pressure (continuous process) cycle. The turbine of the present invention operates on a combination of both cycles, at full power, and mostly on the constant volume cycle at light load.

Other and further objects of this invention will appear from the following description, the accompanying drawings and the appended claim.

Referring to the drawings forming a part of this application:

Fig. 1 is a sectional view, on the line I—I of Fig. 2, of a gas turbine constructed according to the present invention;

Fig. 2 is a section on the line II—II of Fig. 1;

Fig. 3 is a section on the line III—III of Fig. 1;

Fig. 4 is a diagrammatic view of one type of turbine blading for the turbine of Fig. 1;

Fig. 5 is a diagrammatic view of another type of turbine blading for the turbine of Fig. 1;

Fig. 6 is a pressure diagram showing the relative work done by the turbine wheels;

Fig. 7 is a sectional view of a turbine constructed in accordance with a modification of this invention, taken through the combustion chambers and looking toward the inlet ports; and

Fig. 8 is a sectional view through the rotary inlet valve of the turbine of Fig. 7, looking in the opposite direction toward the inlet ports.

The gas turbine of Figs. 1—6 is indicated in the drawings by the reference numeral 1, and includes a front wall 2 and a rear wall 3 spaced by an inner pipe 4 and an outer pipe 5. The inside of pipe 4 provides a chamber 6, and the space between the pipes 4 and 5 provides a chamber 7. The walls 2 and 3 and the pipes 4 and 5 are connected by tie rods 8 and spacers 9. The inside of the pipe 4 and the outside of the pipe 5 are protected by fire brick or some other like material 10 retained by sleeves 11. A shaft 12 is mounted axially in pipe 4 for rotation therein, this shaft 12 having an enlarged hub 13 at its rear end supported in a ball bearing 14 mounted in the pipe 4. A nozzle ring 15 is integral with the hub 13 and overlaps the outer face of the wall 3. The shaft 12 extends at its front end through a central orifice 16 in the wall 2.

A housing 17 is secured to the outer face of wall 2 in any desired manner. This housing has an inlet 18 and an orifice 19 in line with orifice 16, shaft 12 extending through orifice 19 and being journalled in a ball bearing 20 mounted on the outer face of the housing 17. A circular valve 21 is keyed on shaft 12 in housing 17, the circumference of valve 21 being spaced from the

2

surrounding wall of the housing 17 to provide an annular chamber 22 in communication with the inlet 18.

The chamber 7 may be divided by radial partitions into as many combustion chambers as desired. In the instant case three partitions 23 partition the chamber 7 into three combustion chambers 24, 25 and 26. Each partition 23 extends from the wall 2 to the wall 3. However, since the flow of hot gases is toward the wall 3 the center portion of this wall is protected by a cone 27 of fire brick or other material covered by a shield 28, and the partitions 23 are cut to fit snugly against the outer face of the shield 28 and adjacent inner face of the wall 3. The partitions may be secured in place by welding.

Each combustion chamber has an inlet port 29 in the wall 2 and an outlet port 30 in the wall 3. The three ports 29 or the three ports 30 taken together form substantially 360 degrees leaving spacing webs 31 sufficient for fastening to the partitions 23, as is clearly shown in Fig. 2, it being understood that the ports 29 are similar in shape to the ports 30.

The rotary valve 21 is provided with a single port 32 which will register, as the valve rotates, successively with each of the ports 29. Each of the combustion chambers is provided with fuel injection nozzles 33 and an igniter 34, the number of fuel injection nozzles being determined by the axial length of the combustion chamber so that an even distribution of fuel therein is obtained.

The nozzle ring 15 has a nozzle 35 provided with the usual vanes 36, nozzle 35 being substantially 120 degrees in length, or, in other words, about the size and shape of a port 30. As nozzle ring 15 rotates to align its nozzle 35 successively with each of the outlet ports 30, gas leaves each of the combustion chambers in succession. In other words, ports 30 are controlled by nozzle 35 just as ports 29 are controlled by port 32. Since both nozzle ring 15 and valve 21 are rigidly connected to shaft 12, the control of the inlet ports is definitely controlled in relation to the control of the exhaust ports.

A rotor housing 37 is secured to the outer face of the wall 3. It is divided by a central partition 38 into a forward chamber 39 and a rear chamber 40, the nozzle ring 15 being housed in the chamber 39.

The rear wall 41 of housing 37 is provided with an interior hub 42, and hubs 43 and 44 form bearings for the turbine power shaft 45, this shaft 45 extending through a gland and thrust bearing 46 to the exterior of the housing 37. Power can be taken for the rear end of shaft 45 in any desired manner, and it may be geared by reduction gears in any desired manner to drive shaft 12, the gearing therefore being omitted for simplicity.

The nozzle ring 15 has a sealing margin 45 in close proximity with the adjacent wall of the housing 37, and has an inner rear chamber 46 in which is housed the first-stage reaction wheel 47 of the turbine secured on shaft 43. Partition 38 is provided with a circular row of nozzles 48 which form the outlet ports of chamber 39. The partition 38 has a chamber 49 in its rear face housing a constant pressure turbine wheel 50 which may be either of the impulse or reaction type.

The hub 42 is shielded by fire brick or the like 51, contained by a thin shielding member 52 similar to the shield 28. The chamber 39 is provided with a by-pass exhaust port 53 controlled by a valve 54.

The operation of the gas turbine is as follows: The gas turbine must be started by rotation of shaft 12 in any desired well-known manner either mechanically or by flow of air to the turbine wheels. Assuming therefore that the gas turbine is in operation, air under pressure will be flowing through the inlet 18 into the inlet chamber 22. The valve 21 will be rotated by the shaft 12 which can be driven by any desired means, or it can be connected to the turbine power shaft 43 by gears (not shown) in an obvious manner. As valve 21 rotates air from chamber 22 will flow successively into the chambers 24, 25 and 26 through the port 32. The port 32 thus establishes communication with one combustion chamber for the inlet of air and then terminates communication so that combustion can take place in this combustion chamber. Fuel is injected into each combustion chamber by its injection nozzles 33 of which there are sufficient to insure even distribution of fuel throughout the combustion chamber. This injection takes place when the inlet port 29 of the combustion chamber is closed by a sealed portion of the valve 21. Ignition is caused by the igniter 34. The expanding gases rush through the outlet 30 and through the vanes 36 of the nozzle 35 of the nozzle ring 15. The gases can only leave each combustion chamber as the nozzle 35 aligns with the port 30 thereof, and the nozzle ring 15 is accordingly timed with the injection and ignition so that the outlet port 30 of each combustion chamber is open at the proper time for the passage of the high pressure gas to the first-stage reaction wheel 47. Wheel 47 receives the gas with fluctuating pressure and the gas, after expansion in the wheel, enters the chamber 39 where any fluctuations which are left are reduced so that the gas in chamber 39 flows through the continuous nozzle 48 to the second-stage constant pressure turbine wheel 50. The gas is expanded in the wheel 50 and enters the rear chamber 40 only after all the possible work has been taken out of this gas. It is exhausted from the chamber 40 through the outlet thereof.

Should it be desired to operate the gas turbine only by the fluctuating pressure cycle in the first-stage reaction wheel 47, the valve 54 is turned to open position so that the gas is exhausted through the exhaust port 53 without passing through the second-stage wheel 50. The exhaust port 53 will ordinarily be open only when the gas turbine is running at slow speeds and minimum output (light loads). For maximum output the gas turbine will be supercharged, that is instead of atmospheric air being admitted at the inlet 18 air under pressure from a blower, such as a centrifugal blower, will be delivered to the inlet 18, and it is in view of this admission of air under

pressure to the combustion chambers that the constant pressure part of the cycle by expansion in the second-stage wheel 50 becomes necessary.

Because of the combining of two turbine wheels, the first taking care of the expansion of the fluctuating pressure gas, and the second taking care of the expansion of the constant pressure gas, the instant gas turbine will have a greater efficiency than has been obtained in previous gas turbines. It will be noted, by reference to Fig. 1, that the second-stage turbine is a smaller turbine than the first-stage turbine. The cycle is completed without any need for a bulky heat exchanger such as is customarily used in prior art cycles.

The cycle of the instant gas turbine has both a constant volume (explosion) part and a constant pressure (continuous process) part. At light loads the turbine operates mainly on the constant volume part, and at heavy loads most of the work is done by the constant pressure part.

While, as aforesaid, atmospheric air may be admitted at the inlet 18, it is contemplated that air will be delivered to the inlet 18 at constant pressure, but this pressure will be varied with the load so that at very light loads this pressure is practically atmospheric.

The valve 21 is sealed in the housing 17 so that, as is obvious from Fig. 1, leakage is impossible except through the ball bearings 21, and the housing containing this bearing can be packed in any well-known manner to prevent any leakage of air from the chamber 22. Some leakage may occur from the combustion chambers backed into the chamber 22, but this is minimized where air under pressure is admitted to the inlet 18.

Since the nozzle ring 15 only contains a short nozzle 35, the remainder of the nozzle ring acts as a rotating outlet valve sealing off the ports 30 except when it is desired that gas pass therefrom to the turbine wheels.

The work done by the gas turbine is indicated diagrammatically in Fig. 6. The first-stage turbine wheel 47 is designed primarily to convert the variable explosion pressure into work with maximum efficiency. In Fig. 6, the work of one combustion chamber is shown in solid lines. It has two peaks 55 and 56. These peaks indicate part of the work being done by the gases of the combustion chamber 24. The work done by the combustion gases of chambers 25 and 26 is indicated by dotted lines. The air pressure at the inlet 18 is indicated by a dot-dash line 51. The pressure in the chamber 39 is indicated by the line 58.

The peaks 55 and 56 rise above the ordinary inlet pressure of the first-stage turbine wheel 47, this inlet pressure being designated by the line 59 extending on opposite sides of the peaks. Therefore the work done by the first-stage reaction turbine wheel is plotted between the lines 58 and 59 including the peaks 55 and 56. The gas enters the second-stage turbine wheel at the constant pressure indicated by the line 58 and is expanded down to the discharge pressure in chamber 40 indicated by the line 60. This diagram of Fig. 6 shows a full load running condition, and it will be seen that more work is done by the constant pressure second-stage turbine wheel than is done by the fluctuating pressure first-stage reaction turbine wheel. It should, however, be noted that the inlet pressure of the second-stage turbine wheel (line 58) is only slightly less than the air pressure at the inlet 18 (line 51).

The first-stage wheel must be a reaction wheel 75 and the blading of this wheel 47 is so shown in

Figs. 4 and 5 which show diagrammatically two possible arrangements of first- and second-stage turbine wheels. The second-stage or constant pressure turbine wheel 50 can be a reaction wheel 50a, as shown in Fig. 4, or an impulse wheel 50b, as shown in Fig. 5. The reaction blading in all cases has very little curvature at the inlet, as is clearly shown in Figs. 4 and 5. The combustion chambers 24, 25 and 26 are indicated as pipes, and the stationary nozzles 35 and 48 have the same vaning in both cases. It is to be remembered, when referring to Figs. 4 and 5, that the nozzle 35 is relatively short.

For very light loads it has been stated that the inlet pressure at the inlet 18 would be only slightly above atmospheric pressure. Therefore there would be no pressure drop available for the constant pressure stage of the expansion, and if this stage were not eliminated it would result in undesirable losses. Thus at light loads, the valve 54 is turned to open the by-pass exhaust port 53.

Where the rotary valve 21 is driven by the power shaft 43, reduction gearing must be employed since the valve 21 does not rotate at the same speed as the turbine wheels but need only rotate fast enough so that the combined volume of all of the combustion chambers times the number of revolutions is equal to the total volume of air used. The injection and ignition of fuel is timed to give maximum explosion pressure in the combustion chambers at a time when the valve 21 and nozzle ring 15 have sealed off the ports 29 and 30.

No attempt has been made in the drawings to show a gas turbine as it would actually be constructed, but the gas turbine has been shown more or less diagrammatically for simplicity. While expansion of the fluctuating gases has been shown taking place in a single stage rotor 47, and expansion of the constant pressure gases has been shown taking place in a single stage rotor 50, each of the rotors 47 and 50 may be divided into multi-stages in a well-known manner if desired.

Valve 21 may also have incorporated in it a back track duct whose purpose is to allow the flow of gases from a combustion chamber having a slightly higher pressure into a combustion chamber just filled with clean air, thereby pre-compressing this air before the fuel is burned in this second combustion chamber. Such back track duct precompression gives more prompt burning of low grade fuel, as well as effecting an increase in the net cycle efficiency. Such a back track duct would not ordinarily be employed in a gas turbine having only three combustion chambers as shown in Figs. 1 to 5. It is therefore shown in Figs. 7 and 8 in connection with a gas turbine having six combustion chambers. Parts of the modification of the invention shown in Figs. 7 and 8 which correspond to similar parts of the gas turbine of Figs. 1 to 5 are indicated by like references with an accent added.

The only actual change has been an increase in the number of combustion chambers to provide six combustion chambers 61 to 66 inclusive, and the inclusion of a back track duct 67 in the valve 21', the back track duct having an inlet port 68 and an outlet port 69 where the direction of rotation of the shaft 12' is in the direction of the arrow.

In Fig. 8 ports 68 and 69 are shown closed by valves 70, valves 70 being formed by the portions of the front wall 2' between ports 29' thereof. Assuming that chamber 61 has already fired and the gas therein has expanded to the turbine then this chamber will contain residual gas under pressure. Chamber 62 will then be firing and chamber 63 will contain a fresh charge of air. Rotation of the valve 21' will connect chambers 61 and 63 so that the residual gas in chamber 61 can flow backwards through the port 29' into chamber 63 where the residual gas will precompress the charge of air in combustion chamber 63 prior to fuel injection therein. This precompression cycle will be repeated for each of the six combustion chambers.

While there have been hereinbefore described approved embodiments of this invention, it will be understood that many and various changes and modifications in form, arrangement of parts and details of construction thereof may be made without departing from the spirit of the invention, and that all such changes and modifications as fall within the scope of the appended claim are contemplated as a part of this invention.

The invention claimed and desired to be secured by Letters Patent is:

In a gas turbine of the class wherein expanding gas is transmitted under fluctuating pressure from a plurality of combustion chambers through outlet ports in the housing of the combustion chambers to a turbine housing, such ports being controlled by a rotary nozzle ring, in combination, a turbine housing; a turbine shaft in the housing; a first stage reaction turbine on the shaft at the outlet side of the nozzle ring, said turbine being adapted for actuation by variable pressure gas flowing successively from the combustion chambers through the outlet ports into the nozzle ring; a constant pressure chamber at the outlet side of the first stage wheel; a second nozzle ring at the outlet side of the constant pressure chamber; a discharge chamber at the outlet side of the constant pressure nozzle ring; a second stage constant pressure turbine wheel on the shaft in the discharge chamber adapted to be driven by the gas passing through the constant pressure nozzle ring; and a by-pass port in said constant pressure chamber for cutting out said second-stage wheel when said turbine is running at a predetermined load.
